COMBINED NEBULIZER-HUMIDIFIER

William R. King, Denver, and Richard K. Sampson,
Littleton, Colo., assignors to Sandoz-Wander, Inc.,
Hanover, N.J.

Continuation-in-part of design application Ser. No.
203,504, Nov. 30, 1971, which is a continuation-
in-part of design application Ser. No. 151,170,
June 8, 1971, now abandoned. This application
Aug. 27, 1973, Ser. No. 391,789

Term of patent 14 years

Int. Cl. D24—02, 04

U.S. Cl. D83—1 N

FIG. 1

FIG. 2

FIG. 3

FIG. 4

FIG. 1 is a top plan view of a combined nebulizer and humidifier showing our new design;

FIG. 2 is a side elevation view thereof;

FIG. 3 is a side elevation of the side opposite that shown in FIG. 2; and

FIG. 4 is a perspective view taken on a reduced scale.

The broken lines are shown for illustrative purposes only.

This is a continuation-in-part of design application, Ser. No. 203,504, filed Nov. 30, 1971, which application is a continuation-in-part of design application, Ser. No. 151,170, filed June 8, 1971 and now abandoned.

We claim:

The ornamental design for a combined nebulizer-humidifier, as shown and described.
